UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,129,561.

Specification of Letters Patent.

Patented Jan. 5, 1915.

Application filed June 5, 1908. Serial No. 436,755.

To all whom it may concern:

Be it known that I, WILLIAM A. LORENZ, a citizen of the United States, residing at Hartford, in the county of Hartford and 5 State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and more particularly to machines of the front-strike type.

15 One of the objects of the present invention is to provide improved means whereby the platen will at all times be maintained in proper position to receive the types.

Another object thereof is to provide improved means for holding the platen in fixed position during printing, such that the platen may readily be moved forward or backward with respect to the printing plane.

Another object is to provide means where- 25 by the position of the platen with respect to the normal printing plane may at all times be accurately determined.

A further object is to provide means for conveniently setting the platen adjusting 30 mechanism.

Other objects will be in part obvious and in part pointed out hereinafter.

The invention accordingly consists in the features of construction, combinations of ele- 35 ments and arrangement of parts which will be exemplified in the construction herein- after set forth, and the scope of the application of which will be indicated in the following claims.

40 In the accompanying drawings, wherein is illustrated one of the various possible embodiments of my invention; Figure 1 is a view taken transversely through a type- writing machine showing the same; and Fig. 45 2 is a front elevation of a portion of the machine showing the adjustable pointer and dial with which it co-operates.

Similar reference characters refer to similar parts in both views of the drawing.

50 Referring now to the drawing, 1 indicates a portion of the framing of the machine, and 2 represents the rear portion of a center tie-rod which extends transversely of the

machine and at its rear portion is provided with an upwardly extending horn 3 which 55 forms an abutment for the platen carriage 4. The rear portion 2 of the tie-rod is mounted to be moved transversely of the machine and rests upon a slide 5 provided upon the framing of the machine and is 60 also supported and guided in a way 6 depending from a bed 7 supported upon the upper portion of the framework of the machine. The type bars, one of which is shown at 8, are supported in bank upon this bed 65 and are arranged in arcuate form so as to enable them to be projected against a common point upon the platen by mechanism, denoted generally at 10, which is adapted to be connected with a key lever, not shown. 70 11 denotes the platen which, in the present instance, is constituted by a thin metallic strip formed with a plain front face for receiving the impressions of the types, and with a curved rear face which conforms to 75 the contour of the paper roll and lies in contact therewith, the latter being shown conventionally at 12.

The above described mechanism forms no essential part of my invention, the same being shown, described and claimed in patent to W. P. Kidder and C. W. Sponsel No. 879,107, dated Feb. 11th, 1908. A description of said mechanism has been given however, to render the objects of my invention 85 clearer of understanding.

The platen carriage 4, in the present instance, is constituted by a platen frame 13 which is pivotally attached, as at 14, at either end, to a longitudinally and vertically movable rail 15, the latter riding in a shiftable rail 16 connected with a shift lever 17 mounted upon a shift shaft 18. Shift shaft 18 is provided with an arm 19 through which the same is rocked to shift 95 the platen by means of shift mechanism not shown herein connected with said arm. It will be understood however, that when arm 17 is rocked either upwardly or downwardly by shift shaft 18, the entire platen carriage 100 will be correspondingly moved with respect to abutment 3, and that during the letter spacing movements of the carriage, rail 15 will ride on rail 16, balls 20 being interposed between these rails in order to afford a frictionless travel for the platen carriage.

In order to always maintain the platen frame 18 against abutment 3, a spring 21 is interposed between an abutment 22 formed upon rail 15 and a casing 23 formed upon the platen frame. This spring may be adjusted as by means of an adjusting screw 24 so that the platen carriage may be held against the abutment 3 with any desired degree of pressure. An abutment 25 formed upon the platen frame is adapted to engage with abutment 22 of rail 15 and prevent the platen frame from being tilted too far forward.

Shaft 26 which forms the forward end of the tie-rod is threaded into the rear portion 2 thereof at 27 and has its forward end extended through the front wall 28 of the framing of the machine adjacent a dial plate 30 fixed thereon. Shaft 26 is provided with 20 a toothed collar 31 near its forward end, the teeth of which are adapted to mesh with similar teeth formed upon the hub 33 of an adjustable pointer 34 which is adapted to be secured to shaft 26 by means of a screw 35 threaded into the end of said shaft, the teeth of the hub 33 of the pointer meshing with those of collar 31 and operating to hold the pointer 34 in any adjusted position with respect to shaft 26.

30 Dial 30 is so mounted upon the front wall of the machine as to enable pointer 34 to co-operate therewith to indicate to the operator the position of the platen with respect to the printing plane, and is provided with a pair 35 of stops 36 and 37 with which the pointer 34 engages and which limit the rotative movement thereof in either direction.

Having thus described the construction of this embodiment of my invention, the operation thereof may now be understood. By setting the platen 11 in the proper position to receive imprints when a single thickness of paper is interposed between the platen and the types and then releasing the teeth 45 of the pointer from those of the collar 31 of the shaft 26 of the tie-rod, said pointer may be swung around opposite the zero point of the dial, whereupon the pointer may be again clamped to shaft 26, as by 50 means of the screw 35. Then, whenever it is desired to insert additional sheets of paper between the platen and the types, the pointer may be moved over the dial to a position opposite the numerals thereon, said 55 dial, in the present instance, being calibrated to indicate from 0 to 20 sheets. It will thus be seen that the operator may conveniently set the platen into proper position for printing upon any desired number of sheets.

60 When the platen carriage is moved forward and backward by the tie-rod to change the position of the platen with respect to the faces of the types, the platen frame will follow the movements of the abutment 3, which 65 forms the rear portion of the tie-rod by

reason of the fact that it is spring-pressed thereagainst. Therefore, no lost motion can at any time occur between the platen frame and the abutment which might affect the quality of the printing.

70 It will accordingly be seen that I have provided mechanism well adapted to attain, among others, all the objects and ends above enumerated in a simple, yet efficient manner. One of the advantages inherent in the 75 present construction resides in the fact that the platen frame is always maintained in its rearmost position against the abutment of the tie-rod and that the adjustment of the tie-rod in either direction will accurately locate the platen with respect to the printing plane. Moreover, the position of the platen may be readily ascertained by the operator by means of the co-operating dial and pointer.

80 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

85 Having described my invention, what I claim as new and desire to secure by Letters Patent is:—

1. In a typewriting machine, the combination with the platen carriage and the type carriers, of an abutment against which the 100 platen carriage rests, and spring means for holding the platen carriage in engagement with said abutment.

2. In a front-strike typewriting machine, 105 in combination, a platen frame, a platen carried thereby, type adapted to co-act with the platen, a fixed abutment directly back of the printing point adapted to take up the thrust of the type, and means permitting said platen to swing with respect to the 110 printing point.

3. In a typewriting machine, the combination with the platen carriage carrying the platen and a plurality of printing members, 115 of an abutment arranged behind the platen carriage and adapted to furnish a rigid backing therefor, and spring means for holding the platen carriage against said abutment.

4. In a typewriting machine, the combination with a platen carriage and a plurality of printing members, of an abutment disposed behind the platen carriage with respect to which the platen carriage is vertically and longitudinally movable, and spring means for maintaining the platen carriage in engagement with said abutment.

5. In a typewriting machine, the combination with a shiftable and longitudinally movable platen carriage, and printing mem- 120 125 130

bers, of a backing member disposed behind the platen carriage and adapted to hold the same against recession when the platen is engaged by the printing members, and a spring for urging said platen carriage into resilient engagement with said abutment.

6. In a typewriting machine, the combination with the platen carriage carrying the platen, and type bars, of a vertically and longitudinally movable rail to which said platen carriage is hingedly connected, an abutment disposed behind the platen carriage, and spring means interposed between said rail and said platen carriage for holding the latter in engagement with said abutment.

7. In a typewriting machine, the combination with a platen frame, of a platen carried thereby, the type bars, an abutment adapted to slide fore and aft of the machine and extending upwardly behind the platen frame to furnish a rigid backing therefor, a shiftable rail, means for hinging said platen frame to said shiftable rail, and spring means interposed between said shiftable rail and said platen carriage adapted to hold the latter in engagement with said abutment.

8. In a typewriting machine, the combination with a platen frame and a plurality of type bars, of an abutment disposed behind the platen frame and mounted to slide fore and aft of the machine, a vertically and longitudinally movable rail, means for hinging said platen frame upon said rail whereby the same may swing thereon, means for limiting the swinging movement of the platen frame, and spring means for holding it in engagement with said abutment.

9. In a typewriting machine, the combination with a vertically and longitudinally movable rail, of a shiftable rail interposed in the support of said first-mentioned rail and upon which the same travels longitudinally, a platen frame pivotally mounted upon said first-mentioned rail, means for limiting the pivotal movements of said platen frame, an abutment disposed behind the platen frame, and spring means interposed between said first-mentioned rail and the platen frame for holding the latter against said abutment.

10. In a typewriting machine, the combination with the platen carriage comprising a platen frame and a rail hinged thereto, of a vertically shiftable rail upon which said first-mentioned rail is mounted and along which the same is adapted to ride for letter spacing, a plurality of type bars, an abutment disposed behind the platen frame, spring means interposed between the rail of said platen carriage and the platen frame thereof for holding the latter in engagement with said abutment, and means

for preventing the platen frame from tilting forward upon said rail.

11. In a typewriting machine, the combination with the platen carriage comprising a platen frame and a rail hinged thereto, of a vertically shiftable rail upon which said first-mentioned rail is mounted and along which the same is adapted to ride for letter spacing, a plurality of type bars, an abutment disposed behind the platen frame, spring means interposed between the rail of said platen carriage and the platen frame thereof for holding the latter in engagement with said abutment, and co-acting abutments formed upon said rail and the platen frame for preventing the latter from tilting forward.

12. In a typewriting machine, the combination of a platen carriage comprising a vertically and longitudinally movable rail, and a platen frame pivotally mounted upon said rail.

13. In a typewriting machine, the combination of a platen carriage comprising a longitudinally and vertically movable rail, a platen frame hinged to said rail, an abutment disposed behind the platen frame, co-acting abutments upon such rail and platen frame for preventing the former from tilting forward, and a spring interposed between the abutment upon said rail and said platen frame adapted to hold the latter in engagement with said abutment.

14. In a typewriting machine, the combination with the type bars and the platen, of a tension member adjustable in the direction of its length and extending between the platen and a fixed portion of the framing of the machine, an indicating pointer adjustably mounted upon said tension member, and means for holding said tension member and said pointer in fixed relation after relative adjustment.

15. In a typewriting machine, the combination with a platen and the type bars, of a movable abutment disposed behind the platen, an adjustable tension member connected with said abutment and a fixed portion of the framing of the machine and adapted to move said abutment whereby said platen may be moved toward or from the printing plane, a pointer mounted upon said tension member, a dial with which said pointer co-operates, and means whereby said pointer may be adjusted upon said tension member and held in fixed position thereon after adjustment.

16. In a typewriting machine, the combination with the platen and the type bars, of a tie-rod connecting said platen with the fixed portion of the framing of the machine, said tie-rod comprising a pair of relatively adjustable members, one of which is provided with a plurality of teeth, a pointer adjustably mounted upon said last-men-

- tioned member and having a plurality of teeth which mesh with the teeth of said member, and means for locking said teeth in engagement.
17. In a typewriting machine, the combination with the platen and the type bars, of a tie-rod extending between the platen and the front wall of the framing of the machine, said tie-rod being constituted by a pair of relatively adjustable members, one of which is threaded into the other, an indicator pointer adjustably mounted upon one of said members, a scale upon the front wall of the machine with which said pointer co-operates to indicate the position of the platen with respect to the printing plane occupied by the faces of the type bars when they are projected to impression, and means whereby said pointer may be rotatively adjusted with respect to the member upon which it is mounted and for clamping said pointer in fixed position thereon.
18. In a typewriting machine, the combination with the platen carriage and the type bars, of a tie-rod comprising a pair of relatively adjustable members, one of which is extended rearwardly and then upwardly to form a rigid backing for the platen carriage, the other of said members being threaded into the first-mentioned thereof and extended through the front wall of the machine, the forward end of said member being provided with a plurality of teeth, a pointer mounted upon said member and having teeth which mesh therewith, whereby said pointer may be set in different positions thereon, means for locking said pointer in position upon said member, and a dial with which said pointer co-operates to indicate the position of the platen with respect to the common plane assumed by the faces of the types when they are projected to impression.
19. In a front strike typewriting machine, in combination, a carriage comprising a rail shiftable in one transverse direction and held against movement in a transverse direction at right angles thereto, and a platen frame pivotally connected with said rail whereby it may move transversely in said second-mentioned direction.
20. In a typewriting machine, the combination with shifting mechanism, of a platen frame, a pivotally supported shift rail associated with the shifting mechanism along which the platen frame is adapted to travel, means for moving said platen frame transversely to the path of travel of said shift rail, and a hinged connection associated with said platen frame.
21. In a typewriting machine, the combination with a shift rail, of a platen frame adapted to reciprocate along said rail, means for moving said platen frame in a substantially straight line transversely to the length of said rail, and a pivotal connection associated with said platen frame permitting such movement.
22. In a typewriting machine, the combination with pressure-operated type bars having a limited path of travel, of a platen frame having a platen normally disposed at the end of said path of travel, a rail along which said platen frame is adapted to reciprocate, means for moving said platen frame relatively to the end of the path of travel of said type bars, and means associated with said platen frame permitting such movement without moving said rail.
23. In a typewriting machine, in combination, type bars having a limited path of travel, a platen frame, a platen carried thereby normally disposed at the end of the path of travel of said type bars, a shift rail along which the platen frame is adapted to travel, means for moving the platen frame relatively to the end of the path of travel of said type bars and transversely to said shift rail, a hinged connection associated with said platen frame permitting such transverse movement, and means for shifting said rail and frame.
24. In a typewriting machine, in combination, type bars having a limited path of travel, a platen frame, a platen carried thereby normally disposed at the end of the path of travel of said type bars, a shift rail along which the platen frame is adapted to travel, an abutment located behind said platen frame for moving the platen frame relatively to the end of the path of travel of said type bars and transversely to said shift rail, and a hinged connection associated with said platen frame permitting such transverse movement.
25. In a typewriting machine, in combination, type bars having a limited path of travel, a platen frame, a platen carried thereby normally disposed at the end of the path of travel of said type bars, a shift rail along which the platen frame is adapted to travel, an abutment located behind said platen frame for moving the platen frame relatively to the end of the path of travel of said type bars and transversely to said shift rail, a hinged connection associated with said platen frame permitting such transverse movement, and means for holding said platen frame adjacent said abutment.
26. In a front-strike typewriting machine, in combination, a platen frame, a platen carried thereby, type adapted to co-act with the platen, a fixed abutment directly back of the printing point adapted to take up the thrust of the type, means permitting said platen to swing with respect to the printing point, and means adapted to limit the swinging movement of the carriage in both directions while in operative position.

27. In a front-strike typewriting machine, in combination, a platen frame, a platen carried thereby, type adapted to co-act with the platen, a fixed abutment directly back of the printing point adapted to take up the thrust of the type, means permitting said platen to swing with respect to the printing point, means adapted to limit the swinging movement of the carriage in both directions while in operative position, and spring means tending to urge said carriage toward one of its limits of movement.
28. In a front-strike typewriting machine, in combination, a platen frame, a platen carried thereby, type adapted to co-act with the platen, a fixed abutment directly back of the printing point adapted to take up the thrust of the type, means permitting said platen to swing with respect to the printing point, and spring means tending to urge said carriage toward one of its limits of swinging movement.
29. In a front-strike typewriting machine, in combination, a carriage frame, a platen carried thereby, type adapted to co-act with said platen, a carriage rail associated with the carriage frame, a supporting rail, anti-friction devices between said rails, and a pivotal connection associated with the first of said rails adapted to permit the platen to swing with respect to the type.
30. In a front-strike typewriting machine, in combination, a carriage frame, a platen carried thereby, type adapted to co-act with said platen, a carriage rail associated with the carriage frame, a supporting rail, anti-friction devices between said rails, a pivotal connection associated with the first of said rails adapted to permit the platen to swing with respect to the type, and means adapted to limit the swinging movement of the carriage in both directions while still in operative printing position.

In testimony whereof I affix my signature, in the presence of two witnesses.
